UNITED STATES PATENT OFFICE

172,770

ASH TRAY

Ewald W. Terney, Mineola, N. Y.

Application January 28, 1954, Serial No. 28,714

Term of patent 14 years

(Cl. D85—2)

To all whom it may concern:

Be it known that I, Ewald W. Terney, have invented a new, original, and ornamental Design for an Ash Tray, of which the following is a specification, reference being had to the accompanying drawing, forming a part hereof.

Fig. 1 is a perspective view of an ash tray, showing my new design; Fig. 2 is a top plan view of the same; and Fig. 3 is a sectional view taken on the line 3—3 of Fig. 2.

I claim:

The ornamental design for an ash tray, as shown.
